(57) **CLAIM**

The ornamental design for an amusement projectile toy, as shown and described.

DESCRIPTION

FIG. 1 is a side perspective view of an amusement projectile toy showing our new design;

FIG. 2 is an opposite side perspective view thereof;

FIG. 3 is a side view thereof;

FIG. 4 is an opposite side thereof;

FIG. 5 is another side view thereof, rotated 90 degree along the vertical axes;

FIG. 6 is an opposite side view thereof, rotated 180 degrees from the view presented on FIG. 5 along the vertical axes;

FIG. 7 is an enlarged bottom view thereof;

FIG. 8 is an enlarged top view thereof; and,

FIG. 9 is a perspective view of the amusement projectile toy in an alternative position.

The broken lines in FIG. 1, FIG. 6 and FIG. 9 represent portions of the amusement projectile toy that form no part of the claimed design.
